UNITED STATES PATENT OFFICE.

WASYL KAMIANCZYN, OF DUQUESNE, AND ILKO WASYLOW, OF WENDEL, PENNSYLVANIA.

LOCK.

1,216,697.

Specification of Letters Patent. Patented Feb. 20, 1917.

Application filed July 26, 1916. Serial No. 111,335.

To all whom it may concern:

Be it known that I, WASYL KAMIANCZYN, a subject of the Emperor of Austria-Hungary, and a resident of Duquesne, in the 5 county of Allegheny and State of Pennsylvania, and I, ILKO WASYLOW, a subject of the Emperor of Austria-Hungary, and a resident of Wendel, in the county of Westmoreland and State of Pennsylvania, have 10 invented certain new and useful Improvements in Locks, of which the following is a specification.

This invention relates to improvements in locks, particularly of the type adapted for 15 use in connection with swinging doors.

The principal object of the invention is to provide a lock having a bolt operable by a key and other bolt elements operable by a knob.

Another object is to provide an efficient 20 and moderate priced lock in which few elements are employed, and which can be applied to any door of ordinary construction.

These and other objects are attained by 25 the novel construction and combination of parts hereafter described and shown in the accompanying drawing, forming part of this specification and in which:—

Figure 1 is a partial plan and sectional 30 view, the section being taken on line 1—1 of Fig. 3.

Fig. 2 is a partial vertical sectional and front view of the lock, showing its application.

Fig. 3 is a vertical sectional view taken 35 on line 3—3 of Fig. 1, and

Fig. 4 is a fragmental perspective view showing the upper corner of the lock.

In the drawings, the door 10 shows the 40 lock body or casing 11 to be attached at its front edge; in the upper part of the casing are a pair of sliding bolt elements respectively 14 and 15, rigidly engaged together by cross bars 16, near the front and rear 45 ends thereof; the outwardly projecting bevelled ends 17 and 18 of which are shaped in the usual manner and adapted to perform the usual functions of a knob operated latch bolt.

Passing through the door is a rectangular 50 bar 20 having a recess 21 formed near the center of its length, the ends of the bar being secured in the stems 22 of the knobs 23 which are of the usual construction.

Engaged upon the bar in the recess 21 is

a pinion 25, the teeth of which mesh with the rack teeth 28, and 30, formed respectively on the adjacent surface of the bars 14 and 15.

The teeth on the bar 14 are formed entirely across the narrower side of the bar at about the center of its length and with relation to the pinion 25, while the teeth 30, on the oppositely disposed bar 15, are formed on the corresponding adjacent side of the 60 bar 15 within the space of the recess 21, and are, therefore, so much shorter as to permit the pinion 25 to be moved outwardly against the inner surface of the lock casing upon pressure being applied to the knob 23, clearing the teeth 30 and compressing the springs 70 32 and 33, moving the bar 20 laterally through the lock, as will be apparent.

When the knob 23 is pressed inwardly it is possible to turn the same and through it 75 rotate the pinion which by reason of its engagement with the teeth 28, cause the latch bolts 14 and 15 to be retracted within the casing; releasing the knob 23, allows the spring 32 to expand, moving the pinion outwardly into engagement with both racks 80 28 and 30, locking the bolts in whatever position they may be either extended or retracted.

A pull spring 34 is used to keep the bolts 85 14 and 15 normally outward.

Thus far the description pertains to the knob actuated portion of the lock which has also combined with it a sliding lock bolt 35, 90 movable in the casing between fixed bars 36 and 37 respectively, the same being rigidly secured within the casing and forming a slideway therebetween.

One of the bars 37 is provided with a recess 38 and also has attached to it on the 95 outer side a flat spring 40 having an outwardly curved loop 41 adapted to engage the point of an entering key, so that the same is not held rigidly but resiliently in its position when once inserted in the door.

The ward of the key makes contact with the extensions 44 which are movable within the recess 38 and formed with the sliding bolt 35 so as to operate the same under the 100 turning movement of the key inserted through the escutcheon opening 45.

Thus it will be seen that a novel and practical lock has been disclosed possessing certain advantages over those of the common 105 type.

Having thus described our invention, what we claim as new and desire to secure by Letters Patent, is:—

1. In a lock of the type described, a pair of sliding bolts having rack teeth upon their adjacent surfaces, one of said bolts being recessed along said teeth, a pinion normally engaging both of said racks, means for moving said pinion laterally into the mentioned recess and means for rotating said pinion whereby said bolts may be actuated.
2. In a lock of the type described, the combination with a casing, a pair of slide bolts having rigid engaging elements there-

between, one of said bolts being recessed centrally, racks formed on the inner face of said bolts, a pinion normally engaging said racks, a knob operable from the exterior of the door, a bar fixed in said knob whereby rotary motion may be communicated to said pinion, and means for moving said pinion laterally into or out of engagement with the rack on the recessed bolt.

Signed at Irwin, Pa., in the county of Westmoreland and State of Pennsylvania, this 24th day of May, 1916.

WASYL KAMIANCZYN.
ILKO WASYLOW.
